FLOWERPOT STAND

John A. Loeffler, St. Louis, Mo.

Application October 4, 1954, Serial No. 32,516

Term of patent 7 years

(Cl. D35—3)

FIG. 1

FIG. 3

FIG. 2

To all whom it may concern:

Be it known that I, John A. Loeffler, a citizen of the United States, residing in the city of St. Louis, in the State of Missouri, have invented a new, original, and ornamental Design for a Flowerpot Stand, of which the following is a specification, reference being had to the accompanying drawing, forming part thereof.

Figure 1 is a front elevation of a flower pot stand, showing my new design;

Figure 2 is a top plan view of the same; and

Figure 3 is an end elevation of the same.

I claim:

The ornamental design for a flower pot stand, as shown.
